UNITED STATES PATENT OFFICE.

CHARLES E. HUBER, OF MORRISON, ILLINOIS.

CAN-MARKING MACHINE.

1,359,807.

Specification of Letters Patent. Patented Nov. 23, 1920.

Application filed March 1, 1920. Serial No. 362,583.

To all whom it may concern:

Be it known that I, CHARLES E. HUBER, a citizen of the United States, residing at Morrison, in the county of Whiteside and 5 State of Illinois, have invented certain new and useful Improvements in Can-Marking Machines, of which the following is a specification.

My invention has reference to can marking machines, to be used in placing a number upon the end of a can containing condensed milk and similar products. In the canning process it is customary to mark all of the cans containing milk out of the same batch 10 with the same number, so that if, upon testing one or more cans of the batch it shall be discovered that they are unmarketable, the entire batch can be separated and destroyed. The marking of the cans has heretofore been 15 done by means of a rubber stamp, or other unsatisfactory method, requiring considerable time and labor, and the purpose of the present device is to have the cans successively marked by a simple and effective 20 mechanism, as the milk is passing through the canning process. This process consists in passing a succession of cans along a table, at certain points of which said cans are filled and sealed, after which they are delivered to 25 the labeling machine. The movement of the cans through the main machine is necessarily of an intermittent nature, and the herein-after described marking devices are associated with the main machine, and their 30 operation so timed, as to cause the cans to be successively marked with the desired number at the instant when such cans are at rest.

The several features and advantages of the invention will be more fully apprehended 35 from the following specification, reference being had to the drawings accompanying the same, in which:

Figure 1 is a plan view of my invention, with a fragment of the machine with which 40 it is associated, and some of the gear devices indicated in broken lines.

Fig. 2 is a vertical cross-section, along the broken line 2—2 of Fig. 1.

Fig. 3 is an end view of the type-holder 45. Fig. 4 is a top view of one of the arms 33, and

Fig. 5 is a side view thereof.

The main table of the machine is indicated at 6, such table being of circular form, 50 and supported and arranged so as to receive an intermittent rotary movement. Sup-

ported adjacent to the table 6 is an auxiliary table 7, to the lower face of which is fixed a bracket 8, upon which is supported a gear-wheel 9. Connected with the wheel 60 9, so as to rotate therewith, is a hollow shaft 10, extending upwardly into a boxing 11, fixed to the upper face of the table 7. Passing through the shaft 10, so as to have free vertical movement therein, is a spindle 12, 65 rotatable with the shaft 10 by means of a pair of rollers 13 engaged in slots 14 in the upper end of said shaft. The lower end of the spindle 12 is threaded and provided with a thumb-turn 15, between which and the 70 bracket 8 is interposed a coiled spring 16, the tendency of which is to force the spindle 12 downwardly.

Held rigidly in the boxing 11 is a sleeve 75 17, provided at its upper end with a collar 18, in which is a recess 19, having an inclined face 20. Fixed to the spindle 12 above the collar 18 is a collar 21, provided with a lug 22, of similar shape and size to the recess 19. The collar 18 is provided at 80 the opposite side from the recess 19 with another recess similar thereto. This results in the collar 21 and spindle 12 being drawn downwardly twice in each rotation of such spindle. 85

Movement is imparted to the gear-wheel 9 by means of an idler gear 23, supported beneath the table 7, said idler gear being actuated by a gear wheel 25 on a shaft 26. On the same shaft is a gear-wheel 27, in mesh 90 with a large gear wheel 28, supported beneath the table 6, and rotatable therewith. Said last named gear-wheel is commonly found in use with machines containing such tables. By means of the chain of gearing 95 just described, the intermittent movement of the table 6 and gear 28 is communicated to the shaft 10, to impart thereto a half rotation upon each movement of the table 6. This movement is also communicated to the 100 spindle 12, through the rollers 13 and slots 14.

Fixed to the upper end of the spindle 12 is a head 29, provided with a pair of radial projections 30, having heads 31 at their 105 outer ends. Said projections and heads are provided with recesses 32, in which arms 33 are pivoted at their inner ends, so that said arms will swing vertically. At the outer ends of the arms 33 are pins 34, upon which 110 are supported type-holders 35, recessed at their lower ends so as to receive type 36,

provided with desired characters. The parts 35 are held in place by means of latches 35^a, engaging notches in the ends of the pins 34. The arms 33 are held yieldably in elevated position by means of springs 38, secured to the head 29, and bearing against the lower edges of said arms. Secured to the upper edges of the arms 33 are springs 39, ending in plates 40, which have a resilient bearing upon the upper faces of the type-holders 35, permitting a limited rocking movement to said parts.

10 Mounted on one side of the table 7 is a boxing 41, in which is rotatable a pin 42, on the upper end of which is a plate 43, provided with an inking pad 44. Intermittent rotation is imparted to the pin 42 by means of a pulley 45 on the lower end thereof, actuated by a belt 46 from a pulley 47 on the shaft 10.

15 In operation, a series of cans is being moved along the edge of the table 6, in the direction indicated by the arrow. The spindle 12 is given a rotation opposite thereto, causing one or other of the arms 30 to move along for a little distance with the table 6. When the movement of such table is interrupted for an instant, the type-holder is immediately above one of the cans thereon. At the same time the cam 22 drops into one of the recesses 19, letting the spindle 12 and mechanism supported thereby move downwardly with considerable force, caused by gravity and the action of the spring 16. 20 This movement is suddenly interrupted when the collar 21 comes in contact with the collar 18. At this time the marking device which projects over the can is brought into proximity therewith, and the jar resulting from the downward movement and sudden arrest of the spindle and parts attached thereto, forces the marking head and supporting arm downwardly against the action of the spring 38, causing an impact of the 25 type against the end of the can. The spring 38 at once returns such parts to their former positions, and the movement of the cans proceeds. The timing of the parts is such that the arms 30 are alternately turned into 30 position above the table 6. The inking pad 44 is so positioned that when the marking device at the end of one of the arms 30 is operating upon a can, the type of the other one is being provided with a fresh supply 35 of ink. In inking the type the operation is similar to that of marking the cans, the type being brought into proximity to the pad, and then forced downwardly by the sudden jar imparted thereto. In case the top of a 40 can is not exactly level, the type-holder is permitted to rock sufficiently to bring the type into a proper position for printing thereon.

45 The position of the inking devices is such that the type will always come in contact

with the pad at one side of the center thereof, and by reason of the pad being given a rotary movement a new supply of ink is at all times presented to the type.

What I claim and desire to secure, is:

1. A device of the class described, comprising a rotatably mounted member; a supporting member slidably in said first-named member and rotatable therewith; a marking device yieldably held by said supporting member; means for holding said supporting member with said marking device in an inoperative position; means for suddenly releasing the same, so as to bring said marking device into an operative position, with a sudden interruption at the end thereof, giving an independent movement to said marking device; and means for suitably rotating said first-named member.

2. A device of the class described, comprising a member rotatably mounted, and capable of a limited vertical movement; means for imparting to said member an intermittent rotary movement; means for imparting to said member, at the end of each movement, a sudden vertical movement; means for suddenly arresting said last-named movement; a pair of marking devices supported by said member, adapted to be brought alternately into operative position; and means for supplying ink to one of said marking devices coincidently with the marking operation of the other one thereof.

3. In combination with a movable table, an auxiliary stationary table associated therewith; a spindle mounted on said last-named table, so as to be rotatable and vertically movable; a pair of radial arms projecting from said spindle in opposite directions, and adapted to be alternately brought into operative position above said movable table upon said spindle being properly rotated; marking devices yieldably supported in the ends of said arms; means for rotating said spindle; means for imparting to said spindle a vertical movement to give a suitable operation to said marking devices; and an inking device mounted on said stationary table at a point opposite to the point of operation of said marking devices.

4. A device of the class described, comprising a member rotatably mounted and capable of a vertical movement; means for imparting to said member an intermittent rotary movement; means for imparting to said member, at the end of each movement, a sudden vertical movement, means for suddenly arresting said last-named movement; a pair of marking devices supported by said member, adapted to be brought alternately into operative position upon the rotation of said member; an inking device rotatably mounted at a point opposite to the point of operation of said marking devices; and means for imparting to said inking device

a rotary movement coincidently with the movement of said member.

5. A device of the class described, comprising a suitably mounted hollow rotary shaft; a spindle supported therein, so as to be vertically movable and rotatable therewith; marking devices yieldably supported by said spindle; a collar on said spindle, provided with a cam on its lower face; a

member supported beneath said collar and 10 provided with a pair of recesses capable of receiving said cam; means for forcing said spindle downwardly; and means for imparting to said hollow shaft an intermittent rotary movement. 15

In testimony whereof I affix my signature.

CHARLES E. HUBER.
